(57) CLAIM

The ornamental design for a card game board, as shown and described.

DESCRIPTION

FIG. 1 is a perspective view of a card game board; and, FIG. 2 is a top plan view thereof.

The evenly spaced broken lines in the figures are for the purpose of illustrating portions of the card game board which form no part of the claimed design.

The dash-dot broken lines depict the bounds of the claim and form no part of the claimed design.

1 Claim, 2 Drawing SheetsFIG. 1
